CERTAIN (ALPHA-INDENYL-BENZYL)-PYRIDINES
 Charles Ferdinand Huebner, Chatham, N.J., assignor to
 Ciba Corporation, New York, N.Y., a corporation of
 Delaware
 No Drawing. Filed Aug. 17, 1962, Ser. No. 217,518
 14 Claims. (Cl. 260—296)

The present invention relates to pyridine compounds. Primarily, it concerns compounds of the formula:

in which Py represents a pyridyl radical, Ind stands for a 2-(tertiary amino-lower alkyl)-3-indenyl radical, Ph represents a monocyclic carbocyclic aryl group, and R stands primarily for hydrogen, as well as for lower alkyl, salts or quaternary ammonium derivatives of such compounds, as well as process for the preparation of such compounds.

A pyridyl radical stands primarily for 2-pyridyl, but may also represent 4-pyridyl or 3-pyridyl and the like; a pyridyl radical is preferably unsubstituted or may be substituted by lower alkyl, e.g. methyl, ethyl and the like, or any other suitable substituent, such as, for example, lower alkoxy, e.g. methoxy, ethoxy and the like, halogeno, e.g. fluoro, chloro, bromo and the like, or any other suitable functional group.

The lower alkyl portion of the tertiary amino-lower alkyl group of the 2-(tertiary amino-lower alkyl)-3-indenyl radical Ind may be represented by lower alkylene containing from one to seven, preferably from two to three, carbon atoms; such radicals are, for example, 1,2-ethylene, 1-methyl-1,2-ethylene, 2-methyl-1,2-ethylene or 1,3-propylene, as well as methylene, 1,1-ethylene, 1-methyl-1,3-propylene, 1,4-butylene, 1-methyl-1,4-butylene, 1,5-pentylene and the like.

The tertiary amino group of the 2-(tertiary amino-lower alkyl)-3-indenyl substituent Ind may represent, for example, an N,N-di-hydrocarbon-amino group, such as N,N-di-lower alkyl-amino, in which lower alkyl has from one to four carbon atoms, e.g. N,N-dimethylamino, N-methyl-N-ethylamino, N,N-diethylamino, N,N-di-n-propyl-amino, N,N-di-isopropyl-amino, N,N-di-n-butyl-amino, N,N-di-isobutyl-amino and the like, N-cycloalkyl-N-lower alkyl-amino, in which cycloalkyl has from five to seven ring carbon atoms, and lower alkyl has from one to four carbon atoms, e.g. N-cyclopentyl-N-methyl-amino, N-cyclohexyl-N-methyl-amino, N-cyclohexyl-N-ethyl-amino and the like, or N-lower alkyl-N-phenyl-lower alkyl-amino, in which lower alkyl has from one to four carbon atoms, e.g. N-benzyl-N-methyl-amino, N-benzyl-N-ethyl-amino, N-methyl-N- -N - (1-phenylethyl)-amino, N-methyl-N-(2-phenylethyl)-amino and the like, or any other N,N-di-hydrocarbon-amino group. The substituents of the nitrogen atom, particularly lower alkyl, may also have functional groups, such as hydroxyl, lower alkoxy, e.g. methoxy, ethoxy and the like, lower alkyl-mercapto, e.g. methylmercapto, ethylmercapto and the like, or any other suitable group as substituents. N,N-di-hydrocarbon-amino groups, in which the hydrocarbon radical contains functional groups as substituents are, for example, N-hydroxy-lower alkyl-N-lower alkyl-amino, e.g. N-(2-hydroxy-ethyl)-N-methyl-amino and the like, N,N-di-hydroxy-lower alkyl-amino, e.g. N,N-di-(2-hydroxy-ethyl)-amino and the like.

2

The tertiary amino group may also be represented by 1-N,N-alkylene-imino or by 1-N,N-aza-alkylene-imino groups, in which the alkylene portions have from four to six carbon atoms, as well as by 1-N,N-oxa-alkylene-imino and by 1-N,N-thia-alkylene-imino, in which alkylene has preferably four carbon atoms. Together with the nitrogen atom such alkylene, aza-alkylene, oxa-alkylene or thia-alkylene radicals represent, for example, 1-N,N-alkylene-imino, in which alkylene has from four to six carbon atoms, such as 1-pyrrolidino radicals, e.g. 1-pyrrolidino, 2-methyl-1-pyrrolidino and the like, 1-piperidino radicals, e.g. 1-piperidino, 2-methyl-1-piperidino, 4-methyl-1-piperidino, 3-hydroxy-1-piperidino, 3-acetoxy-1-piperidino, 3-hydroxymethyl-1-piperidino, 3-acetoxy-1-piperidino, 3-hydroxymethyl-1-piperidino and the like, 1-N,N-1,6-hexylene-imino and the like, 1-N,N-(aza-alkylene)-imino, in which alkylene has from four to six carbon atoms, particularly 1-N,N-(N-lower alkyl-aza-alkylene)-imino, in which alkylene has from four to six carbon atoms, such as 1-N,N-(3-aza-1,5-pentylene)-imino, particularly 1-N,N-(3-aza-3-lower alkyl-1,5-pentylene)-imino, e.g. 4-methyl-1-piperazino, 4-ethyl-1-piperazino and the like, as well as 4-hydroxyethyl-1-piperazino, 4-acetoxyethyl-1-piperazino and the like, 1-N,N-(3-aza-1,6-hexylene)-imino, e.g. 1-N,N-(3-aza-3-methyl-1,6-hexylene)-imino and the like, or 1-N,N-(4-aza-1,7-heptamethylene)-imino, particularly 1-N,N-(4-aza-4-lower alkyl-1,7-heptamethylene)-imino, e.g. 1-N,N-(4-aza-4-methyl-1,7-heptamethylene)-imino and the like, 1-N,N-(3-oxa-1,5-pentylene)-imino, e.g. 4-morpholino and the like, 1-N,N-(3-thia-1,5-pentylene)-imino, e.g. 4-thiamorpholino and the like.

The 1-position of the 2-(tertiary amino-lower alkyl)-3-indenyl substituent is preferably unsubstituted, or if substituted, contains primarily a hydrocarbon radical, particularly lower alkyl, e.g. methyl, ethyl and the like, or monocyclic carbocyclic aryl-lower alkyl, e.g. benzyl and the like.

The six-membered carbocyclic aryl portion of the 2-(tertiary amino-lower alkyl)-3-indenyl substituent is preferably unsubstituted or may contain one or more than one substituent, which may be located in any of the four positions available for substitution; whenever more than one substituent is present, these may be of the same or of different nature. Such substituents may be, for example, lower alkyl, e.g. methyl, ethyl and the like, halogeno-lower alkyl, e.g. trifluoromethyl, etherified hydroxyl, such as lower alkoxy, e.g. methoxy, ethoxy and the like, or lower alkylenedioxy, e.g. methylenedioxy and the like, esterified hydroxyl, such as lower alkoxy-carbonyloxy, e.g. methoxy-carbonyloxy, ethoxy-carbonyloxy and the like, lower alkanoyloxy, e.g. acetoxy, propionyloxy and the like, or halogeno, e.g. fluoro, chloro, bromo and the like, acyl, such as lower alkanoyl, e.g. acetyl, propionyl and the like, etherified mercapto, such as lower alkyl-mercapto, e.g. methylmercapto, ethylmercapto and the like, nitro, amino, for example, unsubstituted amino, N-mono-substituted amino, such as N-lower alkyl-amino, e.g. N-methylamino and the like, or, preferably, N,N-disubstituted amino, for example, N,N-di-lower alkyl-amino, e.g. N,N-dimethylamino and the like. The six-membered carbocyclic aryl portion of the 2-(tertiary amino-lower alkyl)-3-indenyl substituent Ind may, therefore, be represented, for example, by an unsubstituted, a lower alkyl-substituted, a halogeno-lower alkyl-substituted, a lower alkoxy-substituted, a lower alkylenedioxy-substituted, a lower alkoxy-carbonyloxy-substituted, a

lower alkanoyloxy-substituted, a halogeno-substituted, a lower alkanoyl-substituted, a lower alkyl-mercapto-substituted, a nitro-substituted, an amino-substituted, an N-lower alkyl-amino-substituted or an N,N-di-lower alkyl-amino-substituted six-membered carbocyclic aryl portion.

The monocyclic carbocyclic aryl radical Ph in the above formula represents phenyl, or phenyl-substituted by one or more than one of the same or of different substituents which may be attached to any of the positions available for substitution. Such substituents are, for example, lower alkyl, e.g. methyl, ethyl, isopropyl, n-butyl and the like, lower alkoxy, e.g. methoxy, ethoxy, n-propoxy, isopropoxy and the like, halogeno, e.g. fluoro, chloro, bromo and the like, trifluoromethyl, nitro, amino, such as N,N-di-lower alkyl-amino, e.g. N,N-dimethyl-amino, N,N-diethylamino and the like, or any other suitable group. A substituted phenyl group may, therefore, be represented by (lower alkyl)-phenyl, e.g. 3-methyl-phenyl, 4-isopropyl-phenyl and the like, (lower alkoxy)-phenyl, e.g. 4-methoxy-phenyl, 3,4-dimethoxy-phenyl, 3,4,5-trimethoxy-phenyl, 2-ethoxy-phenyl and the like, (halogeno)-phenyl, e.g. 4-fluoro-phenyl, 3-chloro-phenyl, 2,5-dichloro-phenyl, 4-bromo-phenyl and the like, (trifluoromethyl)-phenyl, e.g. 4-trifluoromethyl-phenyl and the like, (nitro)-phenyl, e.g. 4-nitro-phenyl and the like, (N,N-di-lower alkyl-amino)-phenyl, e.g. 3-N,N-dimethyl-amino-phenyl and the like, or any other suitably substituted phenyl group.

The group R in the above formula represents primarily hydrogen, but it may also stand for lower alkyl, e.g. methyl, ethyl, isopropyl and the like.

Salts of the compounds of this invention are particularly acid addition salts, such as the pharmaceutically acceptable, non-toxic addition salts with inorganic acids, e.g. hydrochloric, hydrobromic, nitric, thiocyanic, sulfuric, phosphoric acids and the like, or with organic acids, e.g. acetic, propionic, maleic, hydroxy-maleic, fumaric, malic, tartaric, citric, methane sulfonic, ethane sulfonic, 2-hydroxyethane sulfonic, ethane 1,2-disulfonic, p-toluene sulfonic acid and the like. Other acid addition salts may be used as intermediates, which may be employed, for example, in the purification of the free compounds or in the preparation of other salts, or for the purpose of identification and characterization. Salts which are primarily used for identification purposes are particularly those with acidic organic nitro compounds, e.g. picric, picrolonic, flavianic acid, or with metal complex acids, e.g. phosphotungstic, phosphomolybdic, chloroplatinic, Reincke acid and the like. Mono- or poly-salts may be formed, depending on the procedure used for the preparation of the salts.

Quaternary ammonium compounds of the above compounds may be either mono- or poly-quaternary ammonium compounds, depending on the conditions of the quaternization reaction and/or the number of tertiary amino groups present. Quaternary ammonium compounds are those with reactive esters of alcohols with acids, particularly the lower alkyl quaternary ammonium halides, sulfates, sulfonates and the like, such as those formed with lower alkyl halides, e.g. methyl chloride, methyl bromide, methyl iodide, ethyl chloride, ethyl bromide, ethyl iodide, n-propyl chloride, n-propyl iodide, isopropyl bromide, isopropyl iodide, n-butyl bromide and the like, di-lower alkyl sulfates, e.g. dimethyl sulfate, diethyl sulfate and the like, lower alkyl lower alkane sulfonates, e.g. methyl methane sulfonate, methyl ethane sulfonate, ethyl methane sulfonate, ethyl ethane sulfonate, n-propyl methane sulfonate and the like, lower alkyl hydroxy-lower alkane sulfonates, e.g. methyl 2-hydroxyethane sulfonate and the like, lower alkyl monocyclic carbocyclic aryl sulfonates, e.g. methyl benzene sulfonate, methyl p-toluene sulfonate, ethyl p-toluene sulfonate and the like, or the monocyclic carbocyclic aryl-lower alkyl, especially the phenyl-lower alkyl, quaternary ammonium

halides, sulfonates, sulfonates and the like, such as those formed with monocyclic carbocyclic aryl halides, especially phenyl-lower alkyl halides, e.g. benzyl chloride, benzyl bromide, benzyl iodide, 2-phenylethyl chloride, 2-phenylethyl bromide and the like, monocyclic carbocyclic aryl-lower alkyl lower alkane sulfonates, particularly phenyl-lower alkyl lower alkane sulfonates, e.g. benzyl methane sulfonate, benzyl ethane sulfonate, 2-phenylethyl methane sulfonate and the like, monocyclic carbocyclic aryl-lower alkyl monocyclic carbocyclic aryl sulfonates, such as phenyl-lower alkyl monocyclic carbocyclic aryl sulfonates, e.g. benzyl benzene sulfonate, benzyl p-toluene sulfonate, 2-phenyl-ethyl p-toluene sulfonate and the like, or any other aliphatic or araliphatic halide, sulfate or sulfonate suitable for the formation of quaternary ammonium derivatives.

Also included as quaternary ammonium compounds are the corresponding quaternary ammonium hydroxides, and other quaternary ammonium salts with acids, particularly with the other acids mentioned hereinabove.

The compounds of this invention may be obtained as mixtures of isomers, e.g. racemates and the like, the separation and resolution of which will be discussed and illustrated hereinbelow.

The compounds of this invention have antispasmodic properties and can be used accordingly, for example, to relieve spastic conditions of smooth muscle tissue, for example, spastic conditions of the gastrointestinal tract, as caused by mental tension, hyperactivity due to food poisoning and the like, or spastic conditions of other smooth muscle tissues, e.g. dysmenorrhea and the like. Particular advantages of the pharmacologically active compounds of this invention are their oral activities and the absence of any other pharmacological effects and side-reactions.

The free bases and the salts thereof, although they, too, have antispasmodic effects, can also be used as intermediates in the manufacture of the quaternary ammonium derivatives; their conversion into the latter will be described hereinbelow.

Non-quaternary ammonium compounds are especially those having the formula

in which A is lower alkylene, Am stands for N,N-di-lower alkyl-amino, N-cycloalkyl-N-lower alkyl-amino, in which cycloalkyl has from five to seven ring carbon atoms, N-lower alkyl-N-phenyl-lower alkyl-amino, 1-N,N-alkylene-imino, in which alkylene has from four to six carbon atoms, 4-morpholino or 1-N,N-(N-lower alkyl-aza-alkylene)-imino, in which alkylene has from four to six carbon atoms, particularly 4-lower alkyl-1-piperazino, R₁ is hydrogen, lower alkyl, trifluoromethyl, lower alkoxy, halogeno, lower alkanoyl or N,N-di-lower alkyl-amino, R₂ stands for hydrogen or lower alkyl, and Ph' is phenyl, (lower alkyl)-phenyl, (lower alkoxy)-phenyl, (halogeno)-phenyl or (trifluoromethyl)-phenyl, or acid addition salts thereof. These compounds, which have antispasmodic properties of their own and may be used accordingly, may also be converted into the quaternary ammonium derivatives according to the procedure described hereinbelow. Quaternary ammonium compounds exerting strong antispasmodic effects are especially the mono-lower alkyl, bis-lower alkyl, poly-lower alkyl, mono-phenyl-lower alkyl, bis-phenyl-lower alkyl or poly-phenyl-lower

alkyl quaternary ammonium halides, sulfates or sulfonates of the compounds having the formula

in which A, Am, R₁, R and Ph' have the previously-given meaning.

Outstanding pharmacological properties are exerted by the 2-{{2-(N,N-di-lower alkyl-amino-lower alkyl)-3-indenyl}phenyl-methyl}-pyridines having the formula

in which A' is lower alkylene, having from two to three carbon atoms, and Am' represents N,N-di-lower alkyl-amino, acid addition salts thereof and the lower alkyl quaternary ammonium halides thereof.

The compounds of this invention may be used in the form of compositions suitable for enteral or parenteral use, which contain the new compounds in admixture with an organic or inorganic, solid or liquid carrier. For making up the preparations there can be employed substances which do not react with the new compounds, such as water, gelatine, lactose, starches, stearic acid, magnesium stearate, stearyl alcohol, talc, vegetable oils, benzyl alcohols, gums, propylene glycol, polyalkylene glycols or any other known carrier used for such preparations. The latter may be prepared according to methods known in the art and may be in solid form, for example, as capsules, tablets, dragees and the like, or in liquid form, for example, as solutions, suspensions, emulsions and the like. If desired, they may contain auxiliary substances, such as preserving, stabilizing, wetting, emulsifying, coloring, flavoring agents and the like, salts for varying the osmotic pressure, buffers, etc. They may also contain, in combination, other useful substances.

The compounds of this invention may be prepared, for example, by reacting an alkali metal compound of an α -(monocyclic carbocyclic aryl)-lower alkyl-pyridine compound of the formula

in which Py, Ph and R have the above-given meaning, with a 2-(tertiary amino-lower alkyl)-indan-1-one, and, if necessary, splitting off the elements of water from a compound containing a 1-hydroxy-2-(tertiary amino-lower alkyl)-1-indanyl substituent by dehydration, and, if desired, converting a resulting salt into the free compound or into another salt, and/or, if desired, converting a resulting compound into a salt or a quaternary ammonium compound thereof, and/or, if desired, converting a quaternary ammonium compound into another quaternary ammonium compound, and/or, if desired, separating a mixture of isomeric compounds into single isomers.

The alkali metal in an alkali metal compound of an α -(monocyclic carbocyclic aryl)-lower alkyl-pyridine is primarily lithium, but may also be another alkali metal, e.g. sodium and the like.

The reaction is carried out according to known methods, especially in the presence of an inert solvent, for example, a hydrocarbon, such as an aliphatic hydrocarbon, e.g.

pentane, hexane and the like, or an aromatic hydrocarbon, e.g. benzene, toluene, xylene and the like, or an ether, such as di-lower alkyl ether, e.g. diethyl ether, di-isopropyl ether and the like, or a cyclic ether, e.g. tetrahydrofuran, p-dioxane and the like, or any other suitable diluent or solvent mixture. The reaction may be carried out while cooling, at room temperature or at an elevated temperature, preferably in the atmosphere of an inert gas, e.g. nitrogen.

- 10 The above-mentioned alkali metal compound of an α -(monocyclic carbocyclic aryl)-lower alkyl-pyridine compound, particularly a lithium derivative, may be formed by reacting an α -(monocyclic carbocyclic aryl)-lower alkyl-pyridine with an aryl metal compound, such as a monocyclic carbocyclic aryl alkali metal compound, e.g. phenyl lithium and the like, or with an aliphatic hydrocarbon alkali metal compound, particularly a lower alkyl lithium derivative, e.g. n-butyl lithium and the like. Such reaction is carried out in the presence of an inert solvent, for example, a lower aliphatic hydrocarbon, e.g. pentane, hexane and the like, an aromatic hydrocarbon, e.g. benzene, toluene, xylene and the like, or an ether, such as a di-lower alkyl ether, e.g. diethyl ether, di-isopropyl ether and the like, or a cyclic ether, e.g. tetrahydrofuran, p-dioxane and the like, or any other suitable diluent or solvent mixture, preferably in the atmosphere of an inert gas, e.g. nitrogen.

The preparation of the α -(monocyclic carbocyclic aryl)-lower alkyl-pyridine alkali metal, particularly lithium, reagent may be modified. Thus, it may also be obtained by treating with lithium an ether formed, for example, by a lower alkanol and an α -hydroxy- α -(monocyclic carbocyclic aryl)-lower alkyl-pyridine; advantageously, such reaction occurs by using a diluted solution of the ether reagent in an inert solvent, particularly in tetrahydrofuran. The resulting solution of the lithium reagent is then reacted with the 2-(tertiary amino-lower alkyl)-indan-1-one compound according to the previously-described procedure.

- 40 The above reaction of the 2-(tertiary amino-lower alkyl)-indan-1-one compound with the alkali metal reagent of an α -(monocyclic carbocyclic aryl)-lower alkyl-pyridine may furnish directly the desired compound having a 2-(tertiary amino-lower alkyl)-3-indenyl substituent, since an intermediately formed compound having a 1-hydroxy-2-(tertiary amino-lower alkyl)-1-indanyl substituent may be dehydrated under the conditions of the reaction and yield directly the desired 2-(tertiary amino-lower alkyl)-3-indenyl substituent. Particularly, direct dehydration takes place if, at any stage of the isolation procedure of the reaction product, acidic conditions are prevailing. If necessary, dehydration of a resulting compound having a 1-hydroxy-2-(tertiary amino-lower alkyl)-1-indanyl substituent may be achieved and completed, for example, by treatment with an acidic reagent, for example, with a mineral acid, e.g. hydrochloric, hydrobromic, sulfuric acid and the like. These acids may be used in the presence of water and/or an organic solvent, such as, for example, glacial acetic acid and the like. Dehydration may also be accomplished by treatment with an organic acid reagent, such as an organic carboxylic acid or an organic sulfonic acid, e.g. oxalic, p-toluene sulfonic acid and the like, or an organic carboxylic acid anhydride, e.g. acetic acid anhydride and the like, or with an inorganic or organic acid halide, e.g. phosphorous oxychloride, acetyl chloride and the like, if desired, in an organic base, e.g. pyridine and the like, if necessary, while heating. Resulting compounds containing a 1-hydroxy-2-(tertiary amino-lower alkyl)-1-indanyl substituent may also lose water at an elevated temperature without the presence of a specific dehydrating agent.

The 2-(tertiary amino-lower alkyl)-indan-1-one compounds used as the intermediates in the above reaction are known, or, if new, may be prepared according to methods used for the manufacture of known analogs. For

example, an α -benzyl-malonic acid ester, such as a lower alkyl, e.g. methyl, ethyl and the like, ester, as well as a suitable heterocyclic, e.g. 2-tetrahydropyranyl and the like, ester, in which the benzyl portion may be unsubstituted or substituted as outlined hereinabove, is treated with a reactive ester formed by a tertiary amino-lower alkanol, in which the tertiary amino group is separated from the hydroxyl group by at least two carbon atoms, and a strong inorganic acid, such as, for example, a mineral acid, e.g. hydrochloric, hydrobromic, hydriodic, sulfuric acid and the like. The reaction produces an α -benzyl- α -(tertiary amino-lower alkyl)-malonic acid ester, in which the tertiary amino group is separated from the α -carbon atom by at least two carbon atoms. This condensation may preferably be carried out in the presence of a base, such as an alkali metal lower alkanolate, e.g. lithium, sodium or potassium methanolate, ethanolate, n-propanolate, isopropanolate or tertiary butanolate and the like. The resulting malonic acid ester may then be cyclized to the 2-(tertiary amino-lower alkyl)-indan-1-one, in which the tertiary amino group is separated from the indane nucleus by at least two carbon atoms. The cyclization may be performed prior or after hydrolysis of the ester groups, which may occur, for example, under alkaline conditions, such as in the presence of an aqueous alkali metal hydroxide, e.g. sodium hydroxide, potassium hydroxide and the like, and, if necessary, subsequent decarboxylation of one carboxyl group, for example, by heating, if desired, in the presence of a mineral acid, e.g. hydrochloric, sulfuric acid and the like. The cyclization may be carried out, for example, by treatment with a strong Lewis acid, such as a strong mineral acid, e.g. anhydrous hydrofluoric, sulfuric, phosphoric acid (preferably in the form of polyphosphoric acid), boron trifluoride (primarily in the form of its etherate), aluminum chloride and the like.

The 2-(tertiary amino-methyl)-indan-1-ones may be prepared by another route, for example, by reacting an indan-1-one with a secondary amine or a salt thereof in the presence of formaldehyde according to the Mannich procedure. Secondary amines are those which furnish the N,N-disubstituted amino groups described hereinbefore; salts of such amines are particularly inorganic acid addition salts, for example, salts with mineral acids, e.g. hydrochloric, hydrobromic, sulfuric acid and the like. The formaldehyde may be used in the form of a solution, e.g. aqueous formaldehyde, as a polymer, e.g. trioxymethylene, paraformaldehyde and the like, or as an acetal with a lower alkanol, e.g. dimethoxy-methane, diethoxyethane and the like. The reaction is advantageously performed in the presence of a solvent, for example, a lower alkanol, e.g. methanol, ethanol and the like, or an aqueous mixture thereof, and/or in the presence of an acid, for example, a mineral acid, e.g. hydrochloric, sulfuric acid and the like, especially when the formaldehyde is employed in the form of a polymer or an acetal thereof. The reaction may be completed by heating, and the resulting 2-(tertiary amino-methyl)-indan-1-one may be isolated as the free base or as an acid addition salt thereof.

A salt resulting from the above procedure may be converted into the free base, for example, by reacting it with an alkaline reagent, such as aqueous alkali metal hydroxide, e.g. lithium hydroxide, sodium hydroxide, potassium hydroxide and the like, aqueous alkali metal carbonate, e.g. sodium or potassium carbonate or hydrogen carbonate and the like, ammonia, or any other suitable alkaline reagent, or with a hydroxyl anion exchange preparation.

A resulting salt may also be converted into another salt, for example, by reacting it with a metal salt, e.g. sodium, barium, silver salt and the like, of an acid in a suitable diluent, in which a resulting inorganic salt is insoluble; the conversion of a salt into another salt may also be carried out by treatment with an anion exchange preparation.

A free base may be converted into an acid addition salt by reacting the former with one of the organic acids mentioned hereinbefore. The salt-forming reaction is carried out, for example, by treating a solution of the free base in a solvent or solvent mixture with the acid or a solution thereof and isolating the desired salt. The salts may also be obtained as the hydrates or may contain solvent of crystallization; mono- or poly-salts may be formed depending on the conditions used for the preparation of the salts.

The quaternary ammonium compounds are prepared according to known methods, for example, by treating the free compound with one of the reactive esters formed by an alcohol and an acid, such as one of those mentioned above. Quaternization may be performed in the absence or presence of a solvent, under cooling, at room temperature or at an elevated temperature, at atmospheric pressure or in a closed vessel under pressure, and, if desired, in the atmosphere of an inert gas, e.g. nitrogen. Suitable diluents are more especially lower alkanols, e.g. methanol, ethanol, n-propanol, isopropanol, tertiary butanol, n-pentanol and the like, lower alkanones, e.g. acetone, ethyl methyl ketone and the like, organic acid amides, e.g. formamide, N,N-dimethylformamide and the like, aliphatic hydrocarbons, e.g. pentane, hexane and the like, halogenated hydrocarbons, e.g. methylene chloride, ethylene chloride and the like, monocyclic carbocyclic aryl hydrocarbon, e.g. benzene, toluene and the like, or any other suitable solvent.

A resulting quaternary ammonium compound may be converted into the corresponding quaternary ammonium hydroxide, for example, by reacting a quaternary ammonium halide with silver oxide, or a quaternary ammonium sulfate with barium hydroxide, or by treating a quaternary ammonium salt with a hydroxyl ion exchange preparation, or by electrodialysis. From a resulting quaternary ammonium hydroxide there may be obtained a quaternary ammonium salt by reacting the base with acid, for example, with one of the acids used in the salt-forming reaction.

A quaternary ammonium compound may also be converted directly into another quaternary ammonium salt without the formation of an intermediate quaternary ammonium hydroxide; for example, a quaternary ammonium iodide may be reacted with freshly prepared silver chloride to yield the quaternary ammonium chloride, or a quaternary ammonium iodide may be converted into the corresponding chloride by treatment of a solution of the former with hydrogen chloride, or the anion of a quaternary ammonium compound, for example, a halide, such as the iodide, may be exchanged for another anion, for example, another halide, such as the chloride, by treatment with a suitable anion exchange preparation, such as, for example, with Amberlite IRA-400 (as described in U.S. Patent No. 2,591,573).

Quaternary ammonium compounds may be isolated as hydrate or may contain solvent of crystallization; depending on the conditions for their formation mono- or poly-quaternary ammonium compounds may be formed.

Mixtures of isomers of resulting compounds may be separated into the single isomers. For example, a mixture of racemates may be separated into individual racemic compounds using known methods, which may be, for example, based on physico-chemical differences, such as solubility. Thus, they may be separated by fractionated crystallization, if necessary, while using a derivative, e.g. a salt or a quaternary ammonium compound of the free base by fractionated distillation and the like.

Racemates of resulting compounds may be resolved into the optically active forms, the levo-rotatory l-form and the dextro-rotatory d-form; resolutions are carried out according to known methods. For example, to a solution of the free base of a racemate (a d,l-compound) in a suitable solvent or solvent mixture is added one of the optically active forms of an acid, containing an asym-

metric carbon atoms, or a solution thereof. Especially useful as optically active forms of salt-forming acids, having an asymmetric carbon atom are the d-tartaric acid (L-tartaric acid) and the L-tartaric acid (D-tartaric acid); the optically active forms of dibenzoyl tartaric, di-p-tolyl-tartaric, malic, mandelic, 10-camphor sulfonic acid, quinic acid and the like, may also be used. Salts which are formed by the optically active forms of the base with the optically active form of the acid may then be isolated, primarily on the basis of their different solubilities. The free and optically active base may be obtained from a resulting salt according to the method outlined hereinbefore, and, if desired, converted into an acid addition salt or a quaternary ammonium compound as shown above. The optically active forms may also be isolated by biochemical methods.

If desired, optically active forms of compounds of this invention, or of salts thereof, may be reconverted into racemates. Racemization may be achieved according to known racemization procedures, for example, by heating of the optically active free base, either with an alkaline reagent, such as, for example, aqueous alkali metal hydroxide, e.g. lithium hydroxide, sodium hydroxide, potassium hydroxide and the like, or an alkali metal, e.g. sodium, potassium and the like, or an alkali metal amide, e.g. sodium amide, potassium amide, and the like, in liquid ammonia, or any other suitable alkaline reagent, or with an acid reagent, such as an inorganic acid, for example, a mineral acid, e.g. hydrochloric, sulfuric acid and the like, or a strong organic acid, for example, a strong organic sulfonic acid, e.g. p-toluenesulfonic acid and the like. Racemization of one of the optically active forms may be advantageously employed to enhance the yield in the formation of the other optically active form which has the opposite rotation; a racemate resulting from such a racemization procedure can then be recycled into the resolution procedure.

The invention also comprises any modification of the process wherein a compound obtainable as an intermediate at any stage of the process is used as starting material and the remaining step(s) of the process is (are) carried out. It also includes any new intermediates, which may be formed in one of the procedures outlined hereinbefore.

In the process of this invention such starting materials are preferably used which lead to final products mentioned in the beginning as preferred embodiments of the invention.

This is a continuation-in-part application of my application Serial No. 144,820, filed October 13, 1961, which in turn is a continuation-in-part application of my application Serial No. 83,618, filed January 19, 1961, both now abandoned.

The following examples are intended to illustrate the invention and are not to be construed as being limitations thereon. Temperatures are given in degrees centigrade.

Example 1

A solution of phenyl lithium (prepared by reacting 1.75 g. of lithium and 20 g. of bromobenzene in 100 ml. of diethyl ether) is slowly added over several hours to a solution of 2-benzyl-pyridine in 50 ml. of anhydrous diethyl ether while stirring and maintaining an atmosphere of dry nitrogen. After standing at room temperature for about four hours, a solution of 10 g. of 2-(N,N-dimethylaminoethyl)-indan-1-one in 50 ml. of anhydrous ether is added dropwise while stirring. The reaction mixture is allowed to stand overnight at room temperature and is then treated with water. The organic material is extracted with an excess of 3N aqueous hydrochloric acid, and the acid extract is heated on the steam bath for thirty minutes, then cooled and basified with ammonia. The organic material is extracted with diethyl ether, the solvent is evaporated, and the residue is dis-

filled to yield the 2-{ α -[2-(N,N-dimethylaminoethyl)-3-indenyl]-benzyl}-pyridine of the formula

which boils at 210°/0.4 mm.

The starting material may be prepared as follows: 33.2 g. of dihydropyran is slowly added to a stirred mixture of 50 g. of α -benzyl-malonic acid and 0.1 g. of p-toluenesulfonic acid in 130 ml. of diethyl ether kept at 30° during the addition of the dihydropyran. The mixture is stirred for an additional 15 minutes and then poured into ice. The ether phase is washed with aqueous potassium carbonate, then with water and is dried over magnesium sulfate; the ether is evaporated under reduced pressure by keeping the temperature below 30° to yield the di-tetrahydropyranyl α -benzyl-malonate. A toluene solution of this ester is gradually given to a solution of 4.86 g. of a 50% suspension of sodium hydride in mineral oil while heating and stirring for six hours. A solution of 10.8 g. of 2-N,N-dimethylaminoethyl chloride in toluene is added dropwise, and the reaction mixture is refluxed for an additional 48 hours. The toluene layer is washed with water, dried over magnesium sulfate and evaporated to yield the di-tetrahydropyranyl α -benzyl- α -(2-N,N-dimethylaminoethyl)-malonate; yield: 32.2 g. of crude material.

A mixture of the resulting di-tetrahydropyranyl α -benzyl- α -(2-N,N-dimethylaminoethyl)-malonate in 180 g. of polyphosphoric acid is stirred at 110-120° during thirty minutes, and then at 150° during an additional twenty minutes. The reaction mixture is cooled, poured into ice-water, the acidic phase is neutralized with potassium carbonate and extracted with ether. The ether solution is washed with 15 percent aqueous hydrochloric acid solution, the aqueous layer is neutralized with potassium carbonate and again extracted with ether. After washing the ether layer with water and drying it over magnesium sulfate, the solvent is evaporated to yield the 2-(2-N,N-dimethylaminoethyl)-indan-1-one; yield: 8 g. of crude material. The hydrochloride of the base melts at 165° after recrystallization from a mixture of ethanol and ether.

Example 2

A solution of 5.0 g. of 2-{ α -[2-(N,N-dimethylaminoethyl)-3-indenyl]-benzyl}-pyridine in 20 ml. of ethanol is treated with 1.3 ml. of methyl iodide. During the addition, the reaction mixture is held at room temperature by cooling in water, and after ten minutes, the precipitate is filtered off. The resulting 2-{ α -[2-(N,N-dimethylaminoethyl)-3-indenyl]-benzyl}-pyridine methiodide or 2-{ α -[2-(N,N,N-trimethylammonio-ethyl)-3-indenyl]-benzyl}-pyridine iodide having the formula

60
65
70
75

is purified by recrystallizing it from ethanol, M.P. 245° (decomposition).

Example 3

The methiodide of 2-{ α -[2-(N,N-dimethylaminoethyl)-3-indenyl]-benzyl}-pyridine obtained according to the procedure of Example 2 is suspended in 50 ml. of

methanol. The solvent is evaporated in an open flask while passing a stream of gaseous hydrogen chloride through the mixture. The syrupy residue is dissolved in 5 ml. of water and concentrated aqueous ammonia is added dropwise until the pH of the solution is about 7. On cooling in the icebox, the 2-{ α -[2-(2-N,N-dimethylaminoethyl)-3-indenyl]-benzyl} - pyridine methochloride or 2-{ α -[2-(2-N,N,N-trimethylammonio-ethyl)-3-indenyl]-benzyl} - pyridine chloride of the formula

crystallizes and is recrystallized from a mixture of ethanol and diethyl ether, M.P. 245-247° (decomposition).

Example 4

A solution of 1.2 g. of { α -[2-(2-N,N-dimethylaminoethyl)-3-indenyl]-benzyl} - pyridine in acetone containing about 1.2 molar equivalents of gaseous methyl chloride, is heated in a closed vessel to about 100° for two hours. On cooling, the desired 2-{ α -[2-(2-N,N-dimethylaminoethyl)-3-indenyl]-benzyl} - pyridine methochloride or 2-{ α -[2-(2-N,N,N-trimethylammonio-ethyl)-3-indenyl]-benzyl} - pyridine chloride precipitates.

Other quaternary ammonium salts of 2-{ α -[2-(2-N,N-dimethylaminoethyl)-3-indenyl]-benzyl} - pyridine, such as the ethiodide, benzyl bromide, methyl monomethyl-sulfate, methyl methane sulfonate and the like, may be prepared by reacting the free base with ethyl iodide, benzyl bromide, dimethyl sulfate, methyl methane sulfonate and the like, respectively, according to the previously-described procedure.

Example 5

A column of 1650 g. of a chlorine anion exchange resin (Amberlite IRA-400, medium porosity, minimum capacity 1.2 meq. per ml., described in U.S. Patent No. 2,591,573), having a diameter of 8.3 cm. and a height of 44.4 cm., is washed with 3500 ml. of methanol. A solution of 330 g. of 2-{ α -[2-(2-N,N-dimethylaminoethyl)-3-indenyl]-benzyl} - pyridine methochloride in 26,000 ml. of methanol is passed through the column during a period of one hour. The resin is washed with 13,000 ml. of methanol, the combined methanol solutions are concentrated to a total volume of 1400 ml. and stirred at room temperature with 33 g. of a charcoal preparation for thirty minutes. The solid material is filtered off and washed with 200 ml. of methanol; the combined filtrate and washing is diluted with 12 ml. of distilled water and 1600 ml. of benzene and concentrated to a volume of 1600 ml. Addition of 1600 ml. of benzene and evaporation to a volume of 1600 ml. is repeated twice; a solid material precipitates during the second solvent replacement. The suspension is chilled at 5° overnight, the solid material is collected, washed with three portions of 150 ml. each of cold benzene and dried at 65° under reduced pressure to yield 238 g. of slightly off-white 2-{ α -[2-(2-N,N-dimethylaminoethyl)-3-indenyl]-benzyl} - pyridine methochloride or 2-{ α -[2-(2-N,N,N-trimethylammonio-ethyl)-3-indenyl]-benzyl} - pyridine chloride, M.P. 236-237°, which is identical with the compound described in Example 3.

Example 6

A mixture of 0.8 g. of 2-{ α -[2-(2-N,N-dimethylaminoethyl)-3-indenyl]-benzyl} - pyridine and 2.5 molar equivalents of methyl iodide is heated in a sealed tube and yields the 2-{ α -[2-(2-N,N-dimethylaminoethyl)-3-indenyl]-benzyl} - pyridine dimethiodide or 2-{ α -[2-(2-N,N,N-tri-

methyl ammonio-ethyl)-3-indenyl]-benzyl} - pyridinium diiodide of the formula

Example 7

To a solution of phenyl lithium (prepared by reacting 1.75 g. of lithium wire and 20.0 g. of bromobenzene in diethyl ether) is added dropwise 21.2 g. of 2-benzyl-pyridine while maintaining room temperature and a nitrogen atmosphere. After standing for 1½ to 2 hours, the deep red mixture is cooled to 0°, and a diethyl ether solution of 12.5 g. of 2-(2-N,N-di-isopropylaminoethyl)-indan-1-one is added dropwise; the reaction mixture is allowed to stand overnight at room temperature. The lithium complex is decomposed by slowly adding water; the organic layer is separated and the aqueous solution is extracted with diethyl ether. The organic extracts are combined and washed with 15 percent aqueous hydrochloric acid. The acidic solution is heated on the steam bath to dehydrate any remaining 2-{ α -[2-(2-N,N-di-isopropylaminoethyl)-1-hydroxy-1-indanyl]-benzyl} - pyridine, and is then cooled and made basic by adding ammonium hydroxide. The organic material is extracted with diethyl ether, the organic layer is separated, washed with water, dried and evaporated. The unreacted starting material is removed from the residue by distillation under reduced pressure (at 0.5 mm.), and the residual 2-{ α -[2-(2-N,N-di-isopropylaminoethyl)-3-indenyl]-benzyl} - pyridine of the formula

is converted into an acid addition salt thereof, for example, into its hydrochloride by adding ethanolic hydrogen chloride to a solution of the base. The 2-{ α -[2-(2-N,N-di-isopropylaminoethyl)-3-indenyl]-benzyl} - pyridine hydrochloride hydrate melts at 140-145° after three recrystallizations from a mixture of ethanol and diethyl ether.

The starting material used in the above reaction is prepared as follows: To a suspension of 0.46 M of sodium hydride in 700 ml. of toluene is added 100.0 g. of diethyl α -benzylmalonate while maintaining a temperature just below the boiling point of toluene. The reaction mixture is refluxed for two hours and is then cooled to 40°. A solution of 83.5 g. of 2-N,N-di-isopropylaminoethyl chloride in toluene is added dropwise, and the reaction mixture is refluxed overnight. The toluene solution is washed with an excess of a mixture of 15 percent aqueous hydrochloric acid and ice; the aqueous extracts are made basic with ammonium hydroxide, and the organic material is extracted with diethyl ether. The organic layer is washed with water, dried over sodium sulfate and evaporated to dryness to yield 157.3 g. of the crude diethyl α -benzyl- α -(2-N,N-di-isopropylaminoethyl)-malonate.

The above crude diethyl α -benzyl- α -(2-N,N-di-isopropylaminoethyl)-malonate is refluxed for four hours in a mixture of 400 ml. of ethanol and 76 g. of potassium hydroxide in 100 ml. of water. The solution is then

evaporated to dryness, the residue is taken up in a minimum amount of water, the solution is acidified with glacial acetic acid, and the desired α -benzyl- α -(2-N,N-di-isopropyl-aminoethyl)-malonic acid is filtered off, washed with ice-water and air-dried overnight, M.P. 135-137°; yield: 88 g. The product is heated at 150° until effervescence ceases. Neither the resulting α -(2-N,N-di-isopropyl-aminoethyl)- β -phenyl-propionic acid nor its hydrochloride are obtained in crystalline form. The oily hydrochloride, prepared by adding ethanolic hydrogen chloride to the base and a minimum amount of ethanol is collected by adding the above solution to a suspension of a diatomaceous earth preparation in diethyl ether, filtering off the mixture, and washing it with diethyl ether.

The above mixture of α -(2-N,N-di-isopropyl-aminoethyl)- β -phenyl-propionic acid hydrochloride and the diatomaceous earth preparation is slowly added to 400 g. of polyphosphoric acid kept at 97-105°. After the addition is completed, the reaction mixture is heated to 100-105° for thirty-five minutes and is then poured onto ice-water. The diatomaceous earth preparation is filtered off, the filtrate is made basic with solid potassium carbonate and the desired 2-(2-N,N-di-isopropyl-aminoethyl)-indan-1-one is extracted with diethyl ether and isolated by washing the organic solution with diethyl ether and evaporating it to dryness. The residue is distilled under reduced pressure; the product boils at 132-134°/0.07 mm.; yield: 30 g.

Example 8

A solution of 0.098 M of phenyl lithium (prepared by reacting 1.372 g. of lithium in 50 ml. of diethyl ether with 15.7 g. of bromobenzene in 50 ml. of diethyl ether) is slowly added to a solution of 16.7 g. of 2-benzylpyridine in diethyl ether while stirring and maintaining an atmosphere of dry nitrogen. After standing at room temperature, a solution of 11.0 g. of 2-(2-N,N-di-n-propyl-aminoethyl)-indan-1-one in diethyl ether is added dropwise while cooling to 0°. The reaction mixture is allowed to stand overnight at room temperature; the excess of the lithium compound is decomposed by slowly adding water, the organic phase is separated and the aqueous layer is extracted with diethyl ether. The diethyl ether extracts are combined and washed with 15 percent hydrochloric acid; the acidic solution is heated on the steam bath for one hour to completely dehydrate any 2-{ α -[2-(2-N,N-di-n-propyl-aminoethyl)-1-hydroxy-1-indanyl]-benzyl}-pyridine, cooled and made basic with ammonium hydroxide. The organic material is extracted with diethyl ether, the organic solution is washed with water, dried and evaporated, and the starting material is separated from the product by distillation under reduced pressure. The residue, representing the 2-{ α -[2-(2-N,N-di-n-propyl-aminoethyl)-3-indenyl]-benzyl}-pyridine of the formula

is converted into an acid addition salt thereof, for example, into its hydrochloride by adding an ethanol solution of hydrogen chloride to a solution of the free base and precipitating the salt by adding diethyl ether; the oily product slowly crystallizes on standing at room temperature, is treated with acetone and the 2-{ α -[2-(2-N,N-di-n-propyl-aminoethyl)-3-indenyl]-benzyl}-pyridine hydrochloride dihydrate melts at 132-135° after recrystallization from a mixture of ethanol and diethyl ether.

The starting material used in the above reaction is prepared as follows: A solution of 303 g. of di-n-propylamine in 440 ml. of water is cooled to room temperature and treated with 70.0 g. of sodium hydroxide. The temperature is adjusted to 40° and 130 g. of ethylene chlorhydrin is added. The reaction mixture is stirred for two hours, allowed to stand overnight and treated with 100.0 g. of sodium hydroxide. The organic layer is separated, dried and distilled to yield the N-(2-hydroxyethyl)-N,N-di-n-propyl-amine, B.P. 90°/18 mm.

10 To a stirred solution of 105.0 g. of thionyl chloride in 176 ml. of benzene is cautiously added 102.0 g. of N-(2-hydroxyethyl)-N,N-di-n-propyl-amine; the reaction mixture is refluxed for two hours, then allowed to stand at room temperature overnight, and the resulting precipitate is filtered off and washed with diethyl ether. The filtrate is concentrated to yield a second crop of crystalline material. The two crops are combined to give the 2-N,N-di-n-propyl-aminoethyl chloride hydrochloride which is recrystallized from a mixture of ethanol and diethyl ether, and converted into the free base by treatment with ammonium hydroxide.

15 To a solution of 8.70 g. of diethyl α -benzyl-malonate in 800 ml. of toluene is added 19.2 g. of a 50 per cent suspension of sodium hydride in mineral oil; after completion of the salt-formation, the reaction mixture is treated with 60.5 g. of 2-N,N-di-n-propyl-aminoethyl chloride, and worked up as shown in Example 7; the diethyl α -benzyl- α -(2-N,N-di-n-propyl-aminoethyl)-malonate hydrochloride, prepared for identification, melts at 80-82°.

20 30 A mixture of 114 g. of diethyl α -benzyl- α -(2-N,N-di-n-propyl-aminoethyl)-malonate and 40.5 g. of potassium hydroxide in 32 ml. of water and 128 ml. of ethanol is refluxed for four hours to yield 57 g. of α -benzyl- α -(2-N,N-di-n-propyl-aminoethyl)-malonic acid after being worked up as shown in Example 7. The dicarboxylic acid is then decarboxylated by heating to 180°; the resulting α -(2-N,N-di-n-propyl-aminoethyl)- β -phenyl-propionic acid does not crystallize, but is converted into its hydrochloride by adding ethanolic hydrogen chloride and pouring the solution into a suspension of a diatomaceous earth preparation in diethyl ether. The resulting solid material is filtered off, washed with diethyl ether, given to 300 g. of polyphosphoric acid at 95-97° and heated at 100-110° for thirty minutes. The reaction mixture is worked up as described in Example 7 and yields 21.2 g. of the 2-(2-N,N-di-n-propyl-aminoethyl)-1-one, B.P. 165°/0.7 mm.

Example 9

35 50 To a solution of phenyl lithium (prepared from 1.75 g. of lithium wire and 20.0 g. of bromobenzene in diethyl ether) is added 21.2 g. of 2-benzyl-pyridine, and the resulting lithium salt is reacted with 12.5 g. of 2-(2-N,N-diethylaminoethyl)-indan-1-one; the reaction is carried out as described in Example 7 and yields the 2-{ α -[2-(2-N,N-diethylaminoethyl)-3-indenyl]-benzyl}-pyridine of the formula

60 65 70 which boils at 202°/0.2 mm.

The starting material used in the above reaction may be prepared as follows: To a warm suspension of 22 g. of sodium hydride in 1,000 ml. of toluene is given dropwise while stirring 100 g. of diethyl α -benzyl-malonate.

The reaction mixture is refluxed for one hour after completion of the addition, then a solution of 70 g. of 2-N,N-diethylaminoethyl chloride in toluene is added and the reaction mixture is refluxed overnight. The toluene solution is extracted with aqueous hydrochloric acid, the acidic layer is made basic with aqueous ammonia and the organic material is extracted with ether. The ether solution is washed, dried and evaporated under reduced pressure to yield 136 g. of diethyl α -benzyl- α -(2-N,N-diethylaminoethyl)-malonate, the oxalate of which melts at 117-119°.

A mixture of 136 g. of diethyl α -benzyl- α -(2-N,N-diethylaminoethyl)-malonate, 65.5 g. of potassium hydroxide, 85 ml. of water and 340 ml. of ethanol is refluxed for 4 hours, then concentrated under reduced pressure. The solid residue is dissolved in a minimum amount of water, the aqueous solution is neutralized with acetic acid while externally cooling and the resulting α -benzyl- α -(2-N,N-diethylaminoethyl)-malonic acid is filtered off and washed with ice water and ethanol. After drying under reduced pressure, it melts at 128°; yield: 103 g.

103 g. of α -benzyl- α -(2-N,N-diethylaminoethyl)-malonic acid is heated to 180° with occasional stirring until foaming ceases; the decarboxylation is complete after approximately 15 minutes. The resulting melt is cooled and diluted with about 15 ml. of ethanol, ether is added and the 2-benzyl-4-N,N-diethylamino-butrylic acid crystallizes, M.P. 102-104°; yield: 83 g.

83 g. of 2-benzyl-4-N,N-diethylamino-butrylic acid is added to 415 g. of polyphosphoric acid, kept at 100-120°. The temperature is then raised to 140-145° for about 20 minutes and the acid is decomposed by pouring the reaction mixture into ice water and neutralizing the aqueous solution with potassium carbonate. The 2-(2-N,N-diethylaminoethyl)-indan-1-one is extracted with ether, the ether solution is washed and dried, and the ether is evaporated. The hydrochloride salt, prepared according to the previously-given procedure, melts at 164-166°; yield: 12.3 g.

Example 10

The 2-{ α -(2-(2-N,N-diethylaminoethyl)-3-indenyl)-benzyl}-pyridine methiodide is prepared by dissolving the 2-{ α -(2-(2-N,N-diethylaminoethyl)-3-indenyl)-benzyl}-pyridine in a small amount of acetone and adding a slight excess of methyl iodide; it separates from the solution, is filtered off and recrystallized from ethanol, M.P. 170-174°.

Other compounds, such as, for example 2-{ α -(2-(2-N,N-dimethylamino-2-methyl-ethyl)-3-indenyl)-benzyl}-pyridine, 2-{ α -(2-(3-N,N-diethylaminopropyl)-3-indenyl)-benzyl}-pyridine, 2-{ α -(2-(2-N,N-diethylaminoethyl)-3-indenyl)- α -phenyl-ethyl}-pyridine, 2-{ α -(2-(2-(1-piperidino)-ethyl)-3-indenyl)-benzyl}-pyridine, 2-{ α -(2-(2-(4-methyl-1-piperazino)-ethyl)-3-indenyl)-benzyl}-pyridine, 2-{ α -(2-(3-(4-morpholino)-propyl)-3-indenyl)-benzyl}-pyridine, 2-{ α -(6-methyl-2-(2-N,N-di-n-propylaminoethyl)-3-indenyl)-benzyl}-pyridine, 2-{ α -(2-(2-N,N-di-isopropylaminoethyl)-6-trifluoromethyl-3-indenyl)-benzyl}-pyridine, 2-{ α -(6-chloro-2-(2-N,N-dimethylaminoethyl)-3-indenyl)-benzyl}-pyridine, 2-{ α -(2-(2-(2-N,N-diethylaminoethyl)-6-methoxy-3-indenyl)-benzyl}-pyridine methiodide, 2-{ α -(6-acetyl-2-(2-N,N-dimethylamino-1-methyl-ethyl)-3-indenyl)-benzyl}-pyridine methobromide, 2-{ α -(2-(2-(2-N,N-diethylaminoethyl)-6-methoxy-3-indenyl)-benzyl}-pyridine methiodide, 2-{ α -(2-(2-(2-N,N-diethylaminoethyl)-3-indenyl)-benzyl}-pyridine methochloride, 2-{ α -(2-(2-N,N-dimethylaminoethyl)-3-indenyl)-3-methyl-benzyl}-pyridine ethochloride, 4-{ α -(2-(2-N,N-dimethylaminoethyl)-3-indenyl)-benzyl}-pyridine dimethiodide, 4-{ α -(3,4-dichloro- α -(2-(2-N,N-diethylaminoethyl)-3-indenyl)-benzyl)-pyridine methochloride, 2-{ α -(2-(2-N,N-dimethylaminoethyl)-3-indenyl)-1-phenylethyl}-pyridine methyl p-toluenesulfonate, 2-{ α -(2-(2-N,N-di-n-propylaminoethyl)-1-methyl-3-indenyl)-benzyl}-pyridine diethiodide and the like, are prepared according to the above-described procedure. The quaternary ammonium derivatives are obtained by reacting the free bases with an appropriate reactive ester, such as a lower alkyl halide, a di-lower alkylsulfate, a lower alkyl organic sulfonate and the like, and, if desired, may be converted into other quaternary ammonium compounds according to the procedures described in Examples 3 and 5.

16
fonates, such as the 2-{ α -(2-(2-N,N-diethylaminoethyl)-3-indenyl)-benzyl}-pyridine methochloride, 2-{ α -(2-(2-N,N-dimethylamino-2-methyl-ethyl)-3-indenyl)-benzyl}-pyridine ethiodide, 2-{ α -(2-(3-N,N-diethylaminopropyl)-3-indenyl)-benzyl}-pyridine methobromide, 2-{ α -(2-(2-N,N-diethylaminoethyl)-3-indenyl)- α -phenyl-ethyl}-pyridine dimethosulfate, 2-{ α -(2-(1-piperidino)-ethyl)-3-indenyl)-benzyl}-pyridine methyl methane sulfonate, 2-{ α -(2-(4-methyl-1-piperazino)-ethyl)-3-indenyl)-benzyl}-pyridine methiodide, 2-{ α -(2-(3-(4-morpholino)-propyl)-3-indenyl)-benzyl}-pyridine n-propyl iodide, 2-{ α -(6-methyl-2-(2-N,N-di-n-propylaminoethyl)-3-indenyl)-benzyl}-pyridine methochloride, 2-{ α -(2-(2-N,N-diisopropylaminoethyl)-6-trifluoromethyl-3-indenyl)-benzyl}-pyridine methiodide, 2-{ α -(6-chloro-2-(2-N,N-dimethylaminoethyl)-3-indenyl)-benzyl}-pyridine methochloride, 2-{ α -(2-(2-N,N-diethylaminoethyl)-6-methoxy-3-indenyl)-benzyl}-pyridine methiodide, 2-{ α -(6-acetyl-2-(2-N,N-dimethylamino-1-methyl-ethyl)-3-indenyl)-benzyl}-pyridine methobromide, 2-{ α -(2-(2-N,N-dimethylaminoethyl)-3-indenyl)-3-methyl-benzyl}-pyridine ethochloride, 4-{ α -(2-(2-N,N-dimethylaminoethyl)-3-indenyl)-benzyl}-pyridine dimethiodide, 4-{ α -(3,4-dichloro- α -(2-(2-N,N-diethylaminoethyl)-3-indenyl)-benzyl)-pyridine methochloride, 2-{ α -(2-(2-N,N-dimethylaminoethyl)-3-indenyl)-1-phenylethyl}-pyridine methyl p-toluenesulfonate, 2-{ α -(2-(2-N,N-di-n-propylaminoethyl)-1-methyl-3-indenyl)-benzyl}-pyridine diethiodide and the like, are prepared according to the above-described procedure. The quaternary ammonium derivatives are obtained by reacting the free bases with an appropriate reactive ester, such as a lower alkyl halide, a di-lower alkylsulfate, a lower alkyl organic sulfonate and the like, and, if desired, may be converted into other quaternary ammonium compounds according to the procedures described in Examples 3 and 5.

What is claimed is:

40 1. A member selected from the group consisting of a compound of the formula

45 in which A is lower alkylene, Am stands for a member selected from the group consisting of N,N-di-lower alkylamino, N-cycloalkyl-N-lower alkyl-amino, in which cycloalkyl has from five to seven ring carbon atoms, N-lower alkyl-N-phenyl-lower alkyl-amino, 1-N,N-alkylene-imino, in which alkylene has from four to six carbon atoms, 4-morpholino and 4-lower alkyl-1-piperazino, R₁ is a member selected from the group consisting of hydrogen, lower alkyl, trifluoromethyl, lower alkoxy, halogeno, lower alkanoyl and N,N-di-lower alkyl-amino, R₂ stands for a member selected from the group consisting of hydrogen and lower alkyl, and Ph' stands for a member selected from the group consisting of phenyl, (lower alkyl)-phenyl, (lower alkoxy)-phenyl, (halogeno)-phenyl and (trifluoromethyl)-phenyl, and pharmaceutically acceptable acid addition salts thereof.

50 2. The member selected from the group consisting of the lower alkyl quaternary ammonium halides, the lower alkyl quaternary ammonium sulfates, the lower alkyl quaternary ammonium sulfonates, the phenyl-lower alkyl quaternary ammonium halides, the phenyl-lower alkyl quaternary ammonium sulfates, the phenyl-lower alkyl

55 75

17

quaternary ammonium sulfonates of a compound of the formula

in which A is lower alkylene, Am stands for a member selected from the group consisting of N,N-di-lower alkyl-amino, N-cycloalkyl-N-lower alkyl-amino, in which cycloalkyl has from five to seven ring carbon atoms, N-lower alkyl-N-phenyl-lower alkyl-amino, 1-N,N-alkylene-imino, in which alkylene has from four to six carbon atoms, 4-morpholino and 4-lower alkyl-1-piperazino, R₁ is a member selected from the group consisting of hydrogen, lower alkyl, trifluoromethyl, lower alkoxy, halogeno, lower alkanoyl and N,N-di-lower alkyl-amino, R₂ is a member selected from the group consisting of hydrogen and lower alkyl, and Ph' stands for a member selected from the group consisting of phenyl, (lower alkyl)-phenyl, (lower alkoxy)-phenyl, (halogeno)-phenyl and (trifluoromethyl)-phenyl.

3. A compound of the formula

in which A' is lower alkylene having from two to three carbon atoms, and Am' stands for N,N-di-lower alkyl-amino.

4. Pharmaceutically acceptable acid addition salts of a compound of the formula

18

in which A' is lower alkylene having from two to three carbon atoms, and Am' stands for N,N-di-lower alkyl-amino.

5. The lower alkyl quaternary ammonium halides of a compound of the formula

10

20

in which A' is lower alkylene having from two to three carbon atoms, and Am' stands for N,N-di-lower alkyl-amino.

6. 2 - { α - [2 - (2 - N,N - dimethylaminoethyl) - 3-indenyl]-benzyl}-pyridine.

7. The lower alkyl quaternary ammonium halides of 2 - { α - [2 - N,N-dimethylaminoethyl] - 3 - indenyl]-benzyl}-pyridine.

8. The 2 - { α - [2 - (2 - N,N - dimethylaminoethyl)-3-indenyl]-benzyl}-pyridine methochloride.

9. The 2 - { α - [2 - (2 - N,N - dimethylaminoethyl)-3-indenyl]-benzyl}-pyridine methiodide.

10. 2 - { α - [2 - (2 - N,N - diethylaminoethyl) - 3-indenyl]-benzyl}-pyridine.

11. 2 - { α - [2 - (2 - N,N - di - n - propyl - aminoethyl)-3-indenyl]-benzyl}-pyridine.

12. Pharmaceutically acceptable acid addition salts of 2 - { α - [2 - (2 - N,N - di - n - propyl - aminoethyl) - 3-indenyl]-benzyl}-pyridine.

13. 2 - { α - [2 - (2 - N,N-di-isopropyl - aminoethyl)-3-indenyl]-benzyl}-pyridine.

14. Pharmaceutically acceptable acid addition salts of 2 - { α - [2 - (2 - N,N - di - iso - propyl - aminoethyl)-3-indenyl]-benzyl}-pyridine.
